UNITED STATES PATENT OFFICE

135,998

DESIGN FOR A BOTTLE

Samuel D. Schneier, Highland Park, N. J.

Application December 15, 1942, Serial No. 109,042

Term of patent 14 years

To all whom it may concern:

Be it known that I, Samuel D. Schneier, a citizen of United States, residing at Highland Park, in the county of Middlesex and State of New Jersey, have invented a new, original, and ornamental Design for a Bottle, of which the following is a specification, reference being had to the accompanying drawing, forming part thereof.

In the drawing

Fig. I is a side elevational view of the narrow side of the bottle showing my new design;

Fig. II is a front elevational view of the broad side of the bottle;

Fig. III is a top plan view;

Fig. IV is a horizontal sectional view of Figure II taken on the line 4—4 looking in the direction of the arrows;

I claim:

The ornamental design for a bottle, as shown.

SAMUEL D. SCHNEIER.
